UNITED STATES PATENT OFFICE.

EDWIN L. WHITE, OF NEW YORK, N. Y., ASSIGNOR TO J. H. WHITE MFG. CO., OF BROOKLYN, NEW YORK, A CORPORATION OF NEW YORK.

DESIGN FOR A METALLIC BAND OR BORDER.

47,940.

Specification for Design.

Patented Oct. 5, 1915.

Application filed April 16, 1915. Serial No. 21,923. Term of patent 7 years.

To all whom it may concern:

Be it known that I, EDWIN L. WHITE, a citizen of the United States, residing at the borough of Brooklyn, in the county of Kings, city and State of New York, have invented a new, original, and ornamental Design for a Metallic Band or Border, of which the following is a specification, reference being had to the accompanying drawing, forming part thereof, in which—

Figure 1 is a front elevation of a band or border showing my new design, and Fig. 2 is an end elevation of the same.

I claim:

The ornamental design for a metallic band or border as shown.

EDWIN L. WHITE.
